UNITED STATES PATENT OFFICE

ERNEST H. SHAFF, OF GRAND HAVEN, MICHIGAN, ASSIGNOR TO WILLIAM H. KELLER, INC., OF GRAND HAVEN, MICHIGAN, A CORPORATION OF MICHIGAN

PRESSURE-FLUID MOTOR

Application filed December 2, 1926. Serial No. 152,107.

This invention pertains generally to pressure fluid motors and particularly relates to improvements in motors of the type described, illustrated and claimed in my co-pending application Serial No. 9,392, filing date February 16th, 1925.

In that application I have described and illustrated a hand held motor device in which a rotary tool is operated by a compressed air motor comprising a circumferentially arranged group of cylinders and pistons acting upon a crank plate providing a series of combined bell cranks which operate to impart a gyratory motion to a pin or arm moving in a conical path. The gyratory motion serves to produce the desired rotation of the tool and likewise to operate a rotating valve member which controls the admission and exhaust of air to and from the cylinders.

It is a further object of this invention to provide an improved construction whereby the number of parts may be lessened and a construction capable of more rapid assembly and economical manufacture.

Another object is to provide an improved method of mounting the crank plate on the crank arm, so as to transmit to the crank arm the power impulses which are successively applied to the crank plate, with increased efficiency.

Another object of the invention is to provide a more advantageous means for attaching the pistons to the gyratory plate to facilitate the assembly thereof.

Other objects and advantages will become apparent as the description of the invention proceeds and also from the accompanying drawings, in which:

Figure 1 represents a longitudinal section of the device as a whole.

Fig. 2 is a vertical cross section of the valve member on the line 2-2 of Fig. 1.

Fig. 3 is a vertical cross section on the line 3-3 of Fig. 1, showing an end view of the cylinder block.

Figs. 4 and 5 are views taken on the lines 4-4 and 5-5 of Fig. 1 showing the opposite sides of the gyratory plate.

Fig. 6 is a longitudinal fragmentary sec-

tion of the cylinder block taken on the line 6-6 of Fig. 3.

Fig. 7 is an enlarged vertical section of the valve mechanism on the line 7-7 of Fig. 8.

Fig. 8 is an enlarged longitudinal section of the valve mechanism on the line 8-8 of Fig. 7.

Fig. 9 is a view similar to Fig. 7, but taken on the line 9-9 of Fig. 8.

Fig. 10 is an enlarged elevation of the rotary sleeve of the valve member.

For purposes of illustration I have herein shown my invention as embodied in a pneumatic rotary drill. This drill comprises a 65 casing having a handle section, a cylinder block, and a crank plate assembly housing. The handle section, designated generally as 11 is herein shown in the form of a pistol grip and includes a manually operable air control 70 mechanism 12, and a valve housing 13. The cylinder block 14 has therein a plurality of radially arranged cylinders 15, within each of which a piston 16 operates to actuate a bell crank plate assembly 17 contained in the 75 housing 18 which is formed as a continuation of the cylinder block and has a drill spindle 19 journaled therein. These three sections are secured in working relation by any suitable means, such as the bolts 20.

Compressed air, under the control of a valve mechanism, to be presently described, is admitted at appropriate intervals to transmit power impulses to the pistons successively, which power impulses are thereupon 85 transmitted to the wobbling bell crank plate or pressure member 17 and thence to a gyratory crank arm shaft 21. The crank arm shaft through suitable connections 22 at one end thereof drives a tool spindle 19 and at 90 the other end is arranged to operate the air-controlling valve mechanism.

It has been found desirable, in devices of this type wherein a plurality of reciprocating parts move at high speed, to provide 95 means for deadening the shock of the parts when such parts reach the end of the return stroke. Such shock may be caused by the fact that during said return stroke under ordinary conditions the parts are under no pres-

sure or tension which might take up any slack, looseness or play in the parts. This play causes them to "slap" together when air is admitted to that cylinder immediately after the piston reaches the end of the exhaust stroke. The means by which I have overcome this objectionable feature comprises an air exhaust under control of the valve mechanism by which the piston is required to exert a slight working pressure to exhaust the final amount of air in the cylinder, thus effectually "cushioning" the return stroke.

As disclosed in the drawings with special reference to Figs. 1-7-8-9-10, the valve mechanism comprises a rotatable cylindrical sleeve 23 mounted in a bushing 24, which is firmly seated in a recess 25 provided in the base of the handle 11. The recess 25 and the bushing 24 are positioned centrally of the base of the handle, which part abuts and is secured to the cylinder block 14. Near the inner end of the recess an internal annular groove 26 is connected to an air supply duct 27 leading through the handle 11 from a suitable source of supply. A plurality of circumferentially arranged ports 28, in number one for each cylinder, are positioned in the bushing to register with the annular groove 26 in the recess, and a second series of somewhat larger, preferably rectangular ports 29 are provided near the outer end of said bushing in axial alignment with the first mentioned ports 28. The second series of ports 29 communicate with a series of passageways 30 which lead to a point adjacent the center of each cylinder.

The sleeve 23 has a peripheral channel 31 (Fig. 9) provided thereon at an appropriate point, which channel during the rotation of the sleeve provides successive communication between each port 28 and its correspondingly aligned port 29. Thus during the rotation of the sleeve 23 air will be admitted to each of the cylinders 15 in progressive sequence through its corresponding port 28, the channel 31 in the sleeve 23, the second port 29 and the passageway 30.

In this instance I have produced the "cushioning" effect through a specially designed exhaust vent in the cylindrical sleeve 23. The vent 32 as shown in Fig. 10, comprises an opening through the sleeve, diagonally disposed from the channel 31, said opening being relatively large at one side and throughout the major portion of its width, but diminishing rapidly to a narrow neck 33 at the other side. The interior of the sleeve 23 has free communication with the atmosphere through an opening 34 in the handle. It will be apparent that as the piston commences its return or exhaust stroke, the air will be exhausted rapidly from the cylinder, during the initial portion of said stroke. However, as the piston nears the end of the exhaust stroke, the narrow neck of the vent moves

into registry with the port, narrowing the size of the vent opening and building up a slight pressure in the cylinder. This pressure, while diminishing, creates a slight resistance which the piston must overcome. Consequently, the movable parts of the assembly are constantly under the influence of forces which tend to hold the parts in the same relative position with a resulting elimination of play, slapping or knocking in the assembly.

In general, the operating mechanism is substantially similar to that set forth in my aforementioned copending application. Thus, it comprises a plurality of bell crank arms provided by the unitary crank plate designated generally as 17 (Fig. 1) and mounted for rotational movement relative to a gyratory crank arm 21. The crank arm is preferably formed integral with a shaft 35 extending rearwardly through the cylinder block 14 and adapted to rotate in a sleeve 36 nonrotatably held therein. Also integral with the crank arm at its front end is a second shaft 37 arranged, through the medium of gears 22, to drive the work spindle 19.

In the construction of the crank plate 17 I prefer to employ a three part construction comprising an inner sleeve 38 secured to an intermediate gear ring 39 on which an outer socket ring 40 is rigidly mounted. The inner sleeve as shown herein is a tubular member fitting into the intermediate ring 39 so as to project rearwardly therefrom. The rear end of this sleeve is offset to provide one ball race 41, and the sleeve is secured firmly to the intermediate gear ring 39 as by a driving fit. The intermediate ring 39 comprises a somewhat cylindrical ring providing at one end a ring gear 42 integral therewith. At the other end of the ring is formed a ball race 43 for a second ball bearing, which is in the nature of a thrust bearing. The outer socket ring is fitted over the intermediate ring preferably from the rear side of the latter, and the two parts are pressed or otherwise rigidly secured together. A pair of appropriate seats 44 provided one on each of the inner and outer surfaces of the intermediate ring 39, are arranged to receive the sleeve 38 and the outer ring 40. At appropriate intervals, depending upon the number of cylinders and pistons in the motor, the outer ring has formed therein a plurality of hemispherical depressions or sockets 45, and seated in each depression is a separate hemispherical cup 46 forming an intermediate socket adapted to receive a ball 47 on the end of a piston rod 48. Suitable means for so securing the parts together may comprise a bolt 49 rigid with and extending from the outer surface of the intermediate socket member or cup 46 through an appropriately positioned opening in the socket 45 and secured in that relation by a nut 50 on the bolt. In this manner a ball and socket

junction between the piston rod 48 and the wobbling crank plate 17 has been effected which may be readily and easily disassembled for purposes of repair or replacement.

5 The piston rod balls 47 which fit into the intermediate sockets, as well as the balls 51 at the opposite ends of the piston rods 48 are preferably hollow for the purpose of eliminating any unnecessary dead weight 10 whose inertia must be overcome at each end of the stroke of the piston.

As shown in Fig. 1, the crank plate, when assembled, has a central opening therethrough at one end of which is the ball race 43 on the intermediate ring 39 and at the other end the ball race 41 on the inner sleeve 38. At either end of the crank arm 21, which extends through the crank plate 17, an enlarged section 52 is cupped to provide ball 20 races 53 and 54 facing the ball races 43 and 41 on the intermediate ring 39 and on the sleeve 38.

As shown in Figs. 1 and 5, the crank arm 21 has a longitudinal bore 55 extending substantially throughout its length, and near the outer end of the bore is an opening 56 which registers with the ball races at that end. A plug 57 mounted on a resilient member such as the U-shaped spring 58 is arranged to be inserted into the opening from within the crank arm and to be held therein by the resilient member acting against the inner walls of the crank arm. Thus I have provided a simple compact and light-weight 35 construction for the crank arm assembly and the mounting therefor, and one which permits the parts to be readily assembled. To do so it is only necessary to insert the crank arm 21 through the central opening in the intermediate ring 39 and sleeve 38, in which 40 positions balls 59 are placed in the lower race formed by the sleeve 38 and the crank arm 21. A second set of balls 60 are then fed into the upper races formed on the ring 39 and the crank arm 21 through the opening 56 in the 45 crank arm, and upon insertion of the plug 57 therein are held securely in the races. Thus the bearing balls serve to hold the crank plate and crank arm in assembled relation.

50 It will be observed, the arrangement is such that the thrust of the pistons is transmitted directly through the outer crank plate ring 40 and the intermediate ring 39 to the thrust bearings on the outer end of the 55 crank arm. Also, it will be seen that the bearings are of relatively small diameter so that their peripheral speeds are reduced to a minimum with a consequent lessening of wear on the parts.

60 As disclosed in my said copending application the crank plate 17 is held against rotation during its wobbling movement as the crank arm 21 rotates in a conical path. Rotation of the plate 17 is prevented by a geared 65 relationship between the ring gear 42 on the

intermediate ring 39 and a bevel gear 61 formed on one end of the sleeve 36 nonrotatably held in the cylinder block 14.

As above indicated, the shaft 35 is formed integrally with the crank arm 21 and extends rearwardly through the cylinder block 14. The outer end thereof is formed to provide an axially-projecting substantially diametrical rib 62 (Figs. 7 and 8) which is arranged to engage a suitable kerf 63 in the end of the 70 rotary sleeve member of the valve mechanism.

It is apparent that I have produced an improved construction of a pressure fluid motor in which the parts are compactly arranged and may be economically manufactured and easily assembled, disassembled or replaced; wherein excess weight has been lessened by the improved construction of certain parts and the elimination of others; and wherein the vibration and noise caused by the slapping, knocking and pounding of the piston and its associated parts during and at the end of the exhaust stroke has been entirely overcome by the "cushioning" effect provided by the valve sleeve, thereby producing a corresponding increase in the efficiency of 80 the motor.

I claim as my invention:

1. In a device of the character described, 90 the combination of a rotatable shaft, an arm on said shaft disposed angularly relative thereto, and means for imparting rotation to said shaft including a plurality of motor units arranged to operate successively, a 100 crank plate rotatably mounted on said arm and operatively connected with said motor units, said plate having a central opening therein adapted to receive said arm, and bearing elements interposed between the arm and the plate at spaced points along the arm, said arm having an opening therein extending radially into one of said spaced points to permit the insertion and removal of certain of said bearing elements.

110 2. In a device of the character described having a gyrating series of bell cranks, a shaft having two ends aligned and an intermediate section offset at an angle thereto and adapted to describe a cone in the rotation of the shaft, a sleeve-like structure about said section constituting an arm common to each of the bell cranks of the series, said section being shaped to form spaced ball races, said sleeve structure providing spaced ball races complementary to the races in said section, and bearing balls for the two sets of complementary races, said shaft section having a passage way extending radially thereof into one of said races to permit the insertion and 120 removal of said balls therefrom.

125 3. In a device of the character described having a gyrating series of bell cranks, the combination of a shaft having a hollow crank arm rigid therewith and disposed at an angle 130

- thereto so as to describe a cone in the rotation of the shaft, a crank plate capable of rotation about said crank arm and providing an arm common to each of the bell cranks of the series, said crank plate comprising two interfitting sections rigidly secured together, and bearing balls interposed between the crank arm and the respective sections of the crank plate at spaced points along the crank arm, said crank arm having a port providing communication with one of said bearings from within said arm to permit the insertion and removal of certain of said balls.
4. In a device of the character described having a gyrating series of bell cranks, the combination of a shaft having a crank arm rigid therewith and disposed at an angle thereto so as to describe a cone in the rotation of the shaft, a crank plate capable of rotation about said crank arm and providing an arm common to each of the bell cranks of the series, and bearing balls interposed between the crank arm and the crank plate at spaced points along the crank arm, said crank arm having a passage way therein extending radially of the axis of one of said spaced bearing points through which certain of said balls may be inserted and removed, and means for closing said passage-way.
5. In a device of the character described having a gyrating series of bell cranks, the combination of a shaft having a crank arm rigid therewith and disposed at an angle thereto so as to describe a cone in the rotation of the shaft, a crank plate capable of rotation about said crank arm and providing an arm common to each of the bell cranks of the series, and bearing balls interposed between the crank arm and the crank plate at spaced points along the crank arm, said crank arm having an axial bore and a radial bore at one of said spaced bearing points to permit the insertion and removal of certain of said balls through said arm.
6. In a device of the character described, an arm rotating upon an axis and a gyrating nonrotating structure on said arm, two bearings arranged in spaced relation longitudinally of the arm and interposed between it and said structure, one of said bearings including a series of rolling elements coacting to hold the structure against axial movement relative to the arm, and said arm having a passage-way extending in part axially of said arm and communicating with one of said bearings to permit insertion and removal of said bearing elements.
7. In a device of the character described, an arm rotating upon an axis and a wabbling non-rotating structure on said arm, bearing means interposed between said structure and said arm and including a series of rolling elements coacting to hold the structure and arm against relative axial movement, one of said parts having an open-
- ing extending substantially perpendicularly to the axis thereof through which said elements may be inserted or removed, and means for closing said opening.
8. In a device of the class described having an arm rotating in a conical path, a wabbling non-rotating plate on said arm, said plate having two ball races facing away from each other, said arm having two ball races facing each other and having an opening therethrough extending in part substantially on the axis of said arm and registering with one of said races whereby the balls for that bearing may be inserted through said opening thereinto, and removable means for closing said opening.
9. A fluid pressure operating device of the character described having, in combination, a gyrating tubular arm rotating about an axis, a pressure plate held thereon against rotation about said axis, a ball race on said arm and said plate faced to receive balls for a ball bearing therebetween, said arm having an opening therein registering with the ball race thereon whereby the balls may be inserted between said races, and means for closing said opening from the inside of said arm.
10. A device of the character described having, in combination, an arm rotating about an axis, a non-rotating pressure plate mounted on said arm, complementary ball races on said arm and said plate, said arm having an opening therein permitting access to said races through said arm whereby balls may be inserted between said races while said plate and arm are in operative relation, and means resiliently held in said opening to prevent the escape of balls therethrough.
11. A device of the character described having, in combination, a gyratory crank arm having thereon a pair of outwardly facing ball races, a shaft integral therewith and extending therefrom at an angle, a non-rotatable sleeve in which said shaft is arranged to rotate, a gear on one end of said sleeve, a crank plate about said crank arm, said plate including a ring having a gear thereon adapted to mesh with said gear on said sleeve to hold said plate against rotation, an inner sleeve about said crank arm rigid with said ring, and a pair of ball races one on said inner sleeve, and one on said ring, each arranged to complement one of the ball races on said crank arm.
12. A pressure fluid actuated tool comprising a casing, a plurality of motor units arranged in circular series in the casing, a shaft having an inclined part disposed on one side of its axis, a pressure member mounted in the casing between said part and said motor units and adapted for oscillatory movement in the operation of said units, said pressure member including an outer annular ring with

- one side of which said motor units are operatively connected, an inner ring fitting into said outer ring from the opposite side of the latter, a sleeve fitting into said inner ring and projecting therefrom in a direction toward said motor units, and bearings interposed between the inclined part of the shaft on the one hand and the inner ring and sleeve respectively on the other.
13. A pressure fluid actuated tool comprising a casing, a plurality of motor units arranged in circular series in the casing, a shaft mounted in the casing and having an inclined portion constituting a crank arm, a pressure member mounted in the casing comprising an outer ring operatively connected with the motor units, an inner ring rigid with the outer ring, a thrust bearing interposed between said inner ring and said arm, an annular member rigid with said inner ring and extending in a direction toward the motor units, another bearing inserted between said annular member and said arm, said pressure member having a gear element rigid therewith, and a stationary gear element mounted in the casing with which the gear element of the pressure member is adapted to coact to prevent rotational movement of the pressure member.
14. In a device of the character described, the combination with a crank arm of a pair of spaced ball races, facing outwardly from the axis of the crank arm a crank plate having a three-part construction including an inner sleeve, an intermediate ring, and an outer ring all rigidly united, said sleeve and said intermediate ring being formed to provide a pair of ball races facing inwardly toward the axis of said sleeve and ring, and bearing balls entered between the inwardly and outwardly facing races.
15. A crank plate member for a motor of the character described comprising a three-part structure including a central tubular sleeve, an outer ring arranged for connection with a plurality of pistons at spaced points about the surface thereof, and an intermediate ring having seats upon its inner and outer surfaces, said inner sleeves and said outer ring being constructed to be rigidly held upon said seats by a driving fit.
16. A pressure fluid actuated tool comprising a casing, a plurality of motor units arranged in circular series in the casing, a shaft disposed axially relative to said series of motor units and having a crank arm rigid therewith, and a pressure member rotatably mounted on said crank arm and comprising a plate having in its periphery a series of sockets, each of said motor units including a piston having a piston rod with a bearing ball thereon, unitary socket members carried by said balls, and means on said socket members engaging said plate removably to secure the sockets in said plate.
17. A crank plate member for a motor of the character described having a plurality of hemispherical depressions therein, a plurality of unitary hemispherical cups adapted to be received in said depressions as sockets for ball and socket connections to said crank plate, and means rigidly mounted on said cups for removably securing said cups in said depressions.
18. A pressure fluid actuated tool comprising, in combination, an arm rotatable upon a fixed axis but inclined relative thereto, a wobbling non-rotating structure mounted on said arm including an annular gear element and a sleeve element secured together in axial alinement with the inner surfaces thereof in registry so as to form an elongated tubular portion to receive said arm, said gear and sleeve elements having ball races at their opposite free ends, said arm being provided with complementary ball races, a plurality of roller elements between said races, a separately formed ring rigid with said tubular portion and extending radially outwardly therefrom, and a plurality of motor units adapted to act upon said ring to impart wobbling movement to said structure and thereby rotation to said arm.
19. In a pressure fluid motor, a gyrating arm having alined end portions integral therewith and rotating about a fixed axis, a three part wobbling structure capable of rotation about said arm and adapted to be slipped over one of said end portions onto said arm, said three part structure comprising a gear element, a sleeve interfitting with said gear element to provide a tubular portion about said arm, and a ring carried by said tubular portion extending radially outwardly therefrom, said gear element and said sleeve each having a ball race thereon facing outwardly from the pivotal axis of said wobbling structure, said arm being provided with ball races complementary to those races formed on said gear element and sleeve, and a plurality of roller elements between said races.
20. In a pressure fluid motor, a gyrating arm and alined end portions integral therewith and rotating about a fixed axis, a sleeve adapted to be slipped over one of said end portions onto said arm, and two series of bearing members interposed between said arm and sleeve at opposite ends thereof, said arm and sleeve constituting two relatively rotatable coaxial elements, one of said elements having a passageway extending radially of the axis of said element through which passageway one series of said bearing members may be inserted and removed.
- In testimony whereof, I have hereunto affixed my signature.
- ERNEST H. SHAFF.
